CLAIM

The ornamental design for the pedicure basin, as shown and described.

DESCRIPTION

FIG. 1 is a right and upper side view of my new pedicure basin, the broken lines shown of a portion of the basin are for illustrative purposes only and form no part of the claimed design;

FIG. 2 is a rear and upper side view of the pedicure basin shown in FIG. 1, the broken lines show of a portion of the basin are for illustrative purposes only and form no part of the claimed design;

FIG. 3 is a top view of the pedicure basin shown in FIG. 1, the broken lines show of a portion of the basin are for illustrative purposes only and form no part of the claimed design; and

FIG. 4 is a left side view of the pedicure basin shown in FIG. 1, the broken lines show of a portion of the basin are for illustrative purposes only and form no part of the claimed design.

FIG. 5 is the front view of the pedicure basin in FIG. 1, the broken lines show of a portion of the basin are for illustrative purposes only and form no part of the claimed design; and,

FIG. 6 is the rear view of the pedicure basin in FIG. 1, the broken lines show of a portion of the basin are for illustrative purposes only and form no part of the claimed design.

The broken line hose has been removed in FIGS. 3 and 6 for convenience of illustration.
